UNITED STATES PATENT OFFICE.

FLORENCE E. TIMMINS, OF SHELBY, NEBRASKA.

DESIGN FOR A TOY WHIP.

No. 38,325.

Specification for Design.

Patented Nov. 27, 1906.

Application filed February 27, 1905. Serial No. 247,623. Term of patent 3½ years.

To all whom it may concern:

Be it known that I, FLORENCE E. TIMMINS, a citizen of the United States, residing at Shelby, in the county of Polk and State of Nebraska, have invented a new, original, and ornamental Design for a Toy Whip, of which the following is a specification.

The figure is a plan view of a toy whip, showing my new design.

I claim—

The ornamental design for a toy whip, as shown and described.

FLORENCE E. TIMMINS.
